UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

MINING-MACHINE TRUCK

Application filed January 21, 1926, Serial No. 82,808. Renewed January 23, 1930.

The present invention relates to certain new and useful improvements in mining machine trucks, and particularly to trucks adapted to cooperate with mine conveyors to move coal cutting machines along the conveyor trough to the place of beginning the cutting operation.

In my copending application Serial No. 743,723, filed October 15, 1924, I have shown a conveyor adapted to extend along a mine working to transport the dislodged coal from the working face to a suitable discharge point in the mine entry where the coal may be loaded into cars suitably positioned upon the mine track. With such an installation the working face upon which the coal cutting machine must operate is commonly situated at a considerable distance from the mine track, and the truck upon which the coal cutting machine is transported along the mine tracks in the mine entry must necessarily remain upon said track. Heretofore it has been necessary to drag the cutting machine over the mine floor by the agency of its feed mechanism, occasioning considerable delay and the expenditure of a great amount of labor.

It is the object of this invention to provide a truck adapted to travel along the conveyor trough and to be actuated by a conveyor chain, to receive the coal cutting machine from the truck upon the mine track in the entry and transport it to the position adjacent the working face where the cutting operation is to begin.

A further object of this invention is to provide a truck of the class described which may readily be knocked down for convenient removal from one part of the mine to another and which may be conveniently and expeditiously assembled in working position relative to the mine conveyor.

These and other objects will be fully set forth in the following specification reference being had to the accompanying drawings of which—

Fig. 1 is a general plan view of the preferred embodiment of my invention.

Fig. 2 is a side elevation of the truck illustrated in Fig. 1 shown in operative relation with a mine conveyor, the side of said con-

veyor trough being broken away to reveal the truck and the conveyor chain.

Fig. 3 is a cross section taken along the line III—III of Fig. 2.

Fig. 4 is a plan view on a reduced scale 55 showing a coal cutting machine in traveling position upon a truck which is in operative relation with the conveyor.

Fig. 5 is a diagrammatic plan view of a room in a coal mine illustrating one method 60 of using the devices of my invention.

Like numerals refer to similar parts in the several figures.

As shown in the drawings my improved truck comprises two elongated similar side sills 1 which are preferably formed of wooden beams of suitable proportions, but which may, if desired, be formed of any other suitable material, such for example as suitably shaped metal beams. To the side sills 1 are attached 65 a plurality of sliding shoes 2 adapted to rest upon and slide over the bottom of the steel trough 3 of a mine conveyor having an endless chain 4 and scraper flights 5 adapted to propel material along said trough. The shoes 2 are preferably formed of wooden blocks for the reason that the coal dust lying upon the bottom of the conveyor trough will be rubbed into the grain of the wood to produce a sliding surface having a low coefficient of friction which needs no lubrication. The shoes 2 are spaced upon the sills 1 at such intervals that the conveyor flights 5 may lie between the ends of adjacent blocks, and as the chain 70 moves, the flights 5 will engage the shoes 2 75 to propel the sills 1 longitudinally along the trough 3. In the conveyor trough here illustrated the side walls 6 of the trough are bent inwardly as shown at 7 in Fig. 3, to engage the ends of the conveyor flights 5 to prevent 80 their riding upon the fragments of coal traveling along the trough. The sliding shoes 2 are extended laterally to form flanges 8 adapted to engage the inward projection of the conveyor trough to prevent the side sills 85 from riding upon the conveyor flights. The numeral 9 refers to a plate which is adapted to rest upon the sills 1, and to the underside of said plate 9 is secured four longitudinally 90 extending angle bars 10 the downwardly pro-

jecting flanges of which engage the edges of the sills 1 to prevent lateral displacement of the plate 9 and to hold the sills 1 in spaced relation with each other. At the center of the plate 9 is a circular aperture adapted to receive a stud 11 which projects downwardly from the center of a plate 12, to the upper face of which is secured two spaced apart transversely extending bars 13 the ends of which are turned upwardly as shown at 14 in Fig. 3. The numeral 15 refers to two longitudinally extending angle bars which are secured in spaced relation by two metal straps 16 riveted to the angle bars and adapted to lie one at either side of the cross bar 13. When these parts are in the relation described and shown the angle bars 15 are supported upon the plate 9 and are held against lateral displacement by the upturned ends 14 of the bar 13 and are held against angular movement relative to the plate by the engagement of the bar 16 with the straps 13. The horizontal flanges 17 of the angle bars 15 are pierced adjacent each end by apertures which are adapted to receive downwardly projecting studs 18 secured to the floor plates 19 and 20 and these studs 18 are transversely pierced by suitable apertures adapted to receive the keys 21 by which the parts are secured in place. When thus assembled the angle bars 15 and floor plates 19 and 20 constitute a truck body adapted to receive and support a coal cutting machine of the well known short-wall type. For convenience in loading or unloading the coal cutting machine upon the truck its body may be rocked upon the cross bar 13 to tilt the angle bars 15 into contact with the mine floor, and it may be turned about the stud 11 to the preferred angular relation with the longitudinal lines of the conveyor.

In Fig. 5 of the drawing I have illustrated a typical installation comprising a mine entry 22 and a mine room 23. In the entry 45 there is provided the customary track 24 along which travel the mine cars by which dislodged coal is transported from the mine. Extending from the entry longitudinally of the mine room is a conveyor 25 of the well known chain and scraper type by which the dislodged coal may be transported from the working face in the mine room to the cars positioned upon the track 24 in the entry. The principal mining operations occur upon 50 the long face 26 of the room 23 which extends parallel with the conveyor 25, and suitable gathering mechanism, not shown in the drawings, is commonly employed to gather the dislodged coal from the floor of the mine 55 and transfer it to the conveyor 25 to be loaded into the cars upon the mine track. After all of the dislodged coal has been removed from the room 23 a suitable coal cutting mechanism indicated at 27 in Fig. 5 of the drawing, will 60 be brought into the room and operated to

undercut the coal along the face 26, beginning at the inner end of the face and terminating at the outer end adjacent the entry. Coal cutting machines such as are here contemplated are provided with trucks 28 adapted to travel along the tracks of the mine to transport the machine from one working place to another. Since the coal is delivered to the mine cars in the entries no branch tracks are laid into the rooms, and this necessitates the discharge of the mining machine 27 from the truck 28 at a point in the entry adjacent the mouth of the room. In order that the mining machine 27 may be conveniently and expeditiously transferred to the 75 point of beginning the undercutting operation in the mine room, my improved truck 29 may be assembled upon the conveyor 25, in the manner above described, its body placed in longitudinal alignment with the 80 body of the truck 28 upon the mine track and the mining machine 27 transferred from the truck 28 to the truck 29. The conveyor chain 4 may then be actuated to propel the truck 29 to the place of beginning the cutting operation where the mining machine 27 may be unloaded in the manner which is well understood by those skilled in the art. After the completion of the cutting operation the truck 29 may be moved to proximity with the mining machine 27, and the machine may be then reloaded onto the truck and from it transferred to the truck 28 in the mine entry, to be transported to the next working place. After the completion of the cutting operation and the removal of the mining machine from the truck 29, said truck may be disassembled thereby leaving the conveyor trough unobstructed for the transfer of broken coal to the mine cars as above described. 95

What I claim is:—

1. In an apparatus of the class described, the combination with a conveyor comprising a trough, a flexible draft member movable longitudinally thereof, and material engaging elements attached to said draft member adapted to propel material along said trough, of a machine transporting body adapted to travel along said trough and to engage said material engaging elements to be propelled thereby as and for the purpose set forth. 110

2. In an apparatus of the class described, the combination with a conveyor comprising a trough, a flexible draft member movable longitudinally thereof, and material engaging elements attached to said draft member adapted to propel material along said trough, of a machine transporting body adapted to travel upon the bottom of said trough and to engage said material engaging elements to be propelled thereby as and for the purpose set forth. 120

3. In an apparatus of the class described, the combination with a conveyor comprising a trough, a flexible draft member movable 130

longitudinally thereof, and material engaging elements attached to said draft member adapted to propel material along said trough, of a machine transporting body adapted to slide upon the bottom of said trough and to engage said material engaging elements to be propelled thereby as and for the purpose set forth.

4. In an apparatus of the class described, the combination with a conveyor comprising a trough, a flexible draft member movable longitudinally thereof, and material engaging elements attached to said draft member adapted to propel material along said trough, of a machine transporting body having supporting shoes adapted to slide upon the bottom of said trough and arranged to engage said material engaging elements to be propelled thereby as and for the purpose set forth.

5. In an apparatus of the class described, the combination with a conveyor comprising a trough, a flexible draft member movable longitudinally thereof, and material engaging elements attached to said draft member adapted to propel material along said trough, of a machine transporting body adapted to be propelled along said trough by said material engaging elements, and a machine supporting frame mounted upon said body as and for the purpose set forth.

6. In an apparatus of the class described, the combination with a conveyor comprising a trough, a flexible draft member movable longitudinally thereof, and material engaging elements attached to said draft member adapted to propel material along said trough, of a machine transporting body adapted to be propelled along said trough by said material engaging elements, and a machine supporting frame removably mounted upon said body adapted to support a mining machine for transportation along said trough as and for the purpose set forth.

45 7. In an apparatus of the class described, the combination with a conveyor comprising a trough, a flexible draft member movable longitudinally thereof, and material engaging elements attached to said draft member adapted to propel material along said trough, of a machine transporting body adapted to be propelled along said trough by said material engaging elements, and a machine supporting frame pivotally mounted upon said body adapted to support a mining machine for transportation along said trough as and for the purpose set forth.

8. In an apparatus of the class described, the combination with a conveyor comprising a trough, a flexible draft member movable longitudinally thereof, and material engaging elements attached to said draft member adapted to propel material along said trough, of a machine transporting body adapted to be propelled along said trough by said ma-

terial engaging elements, and a machine supporting frame pivotally mounted upon said body for rotation about a vertical axis and adapted to support a mining machine for transportation along said trough as and for the purpose set forth.

9. In an apparatus of the class described, the combination with a conveyor comprising a trough, a flexible draft member movable longitudinally thereof, and material engaging elements attached to said draft member adapted to propel material along said trough, of a machine transporting body adapted to be propelled along said trough by said material engaging elements, and a machine supporting frame tiltably mounted upon said body and adapted to receive or discharge a mining machine from or to the floor of a mine as and for the purpose set forth.

10. In an apparatus of the class described, the combination with a conveyor comprising a trough, a flexible draft member movable longitudinally thereof, and material engaging elements attached to said draft member adapted to propel material along said trough, of a machine transporting body adapted to be propelled along said trough by said material engaging elements, and a machine supporting frame mounted upon said body for pivotal movement about a vertical axis and tiltable about a horizontal axis adapted to receive or discharge a mining machine from or to the floor of a mine as and for the purpose set forth.

11. In an apparatus of the class described, the combination with a conveyor comprising a trough, a flexible draft member movable longitudinally thereof, and material engaging elements attached to said draft member and adapted to propel material along said trough, of a machine transporting body adapted to travel along said trough and comprising a pair of sills adapted to be positioned within said trough to extend longitudinally thereof and to engage said material engaging elements to be propelled thereby as and for the purpose set forth.

12. In an apparatus of the class described, the combination with a conveyor comprising a trough, a flexible draft member movable longitudinally thereof, and material engaging elements attached to said draft member and adapted to propel material along said trough, of a machine transporting body adapted to travel along said trough and comprising a pair of sills adapted to be positioned within said trough to extend longitudinally thereof, and supporting shoes attached to said sills adapted to slide upon the bottom of said trough and arranged to engage said material engaging elements to be propelled thereby along said trough as and for the purpose set forth.

13. In an apparatus of the class described, the combination with a conveyor comprising

a trough, a flexible draft member movable longitudinally thereof, and material engaging elements attached to said draft member and adapted to propel material along said trough, of a machine transporting body adapted to travel along said trough, propelled by said material engaging elements and comprising a pair of sills adapted to be positioned within said trough to extend longitudinally thereof, and a machine supporting frame removably mounted upon said sills adapted to support a mining machine for transportation along said conveyor as and for the purpose set forth.

14. In an apparatus of the class described, the combination with a conveyor comprising a trough, a flexible draft member movable longitudinally thereof, and material engaging elements attached to said draft member and adapted to propel material along said trough, of a machine transporting body adapted to travel along said trough propelled by said material engaging elements and comprising a pair of sills adapted to be positioned within said trough and to extend longitudinally thereof, a plate adapted to be positioned upon said sills and having downwardly projecting flanges adapted to engage their sides to hold said sills in spaced parallelism, and a machine supporting frame removably mounted upon said plate adapted to support a mining machine for transportation along said conveyor as and for the purpose set forth.

15. In an apparatus of the class described, the combination with a conveyor comprising a trough, a flexible draft member movable longitudinally thereof, and material engaging elements attached to said draft member and adapted to propel material along said trough, of a machine transporting body adapted to travel along said trough propelled by said material engaging elements and comprising a pair of sills adapted to be positioned within said trough and to extend longitudinally thereof, a plate adapted to be positioned upon said sills and having downwardly projecting flanges adapted to engage their sides to hold said sills in spaced parallelism and a machine supporting frame pivotally mounted upon said plate adapted to support a mining machine for transportation along said conveyor as and for the purpose set forth.

16. In an apparatus of the class described, the combination with a conveyor comprising a trough, a flexible draft member movable longitudinally thereof, and material engaging elements attached to said draft member and adapted to propel material along said trough, of a machine transporting body adapted to travel along said trough propelled by said material engaging elements and comprising a pair of sills adapted to be positioned within said trough and to extend longitudinally thereof, a plate adapted to be po-

sitioned upon said sills and having downwardly projecting flanges adapted to engage their sides to hold said sills in spaced parallelism, a turntable removably mounted upon said plate and longitudinally extending angle bars removably attached to said turntable adapted to receive and support a mining machine for transportation along said trough as and for the purpose set forth.

17. In an apparatus of the class described, the combination with a conveyor comprising a trough, a flexible draft member movable longitudinally thereof, and material engaging elements attached to said draft member and adapted to propel material along said trough, of a machine transporting body adapted to travel along said trough propelled by said material engaging elements and comprising a pair of sills adapted to be positioned within said trough and to extend longitudinally thereof, a turntable removably mounted upon said sills, longitudinally extending angle bars removably attached to said turntable and adapted to receive and support a mining machine for transportation along said trough, and removable means adapted to secure said angle bars in spaced parallelism as and for the purpose set forth.

In testimony whereof I have hereunto set my hand.

NILS D. LEVIN.
